LUBRICANT COOLING MEANS FOR SEWING MACHINES

Hans Hacklander, Warren Township, N.J., assignor to The Singer Manufacturing Company, Elizabeth, N.J., a corporation of New Jersey

Filed June 27, 1958, Ser. No. 745,065

4 Claims. (Cl. 112—256)

The present invention relates to sewing machines and particularly to a lubricant cooling means for sewing machines.

In modern high speed industrial sewing machines which operate at speeds upwardly of 5,000 stitches per minute, the agitation of the lubricant in the bed of the machine causes excessive heating of the lubricant which necessitates the use of a lubricant cooling means. However, these high operating speeds are attained only in a so-called straight-away sewing machine, or in other words, in a sewing machine which produces a limited number of lines of stitching such as one or two, or does not have auxiliary mechanism such as a ruffing mechanism, a differential or other auxiliary feeding mechanism, a trimming mechanism or a thread laying mechanism. When a machine is so equipped, the additional load of the mechanism limits the machine to a relatively low maximum operating speed. At the same time, the mechanics and inertia of the mechanisms as well as the fact that greater manipulation of the work and skill is required in operating a sewing machine having the auxiliary mechanisms, makes it impractical to operate such a machine at an extremely high speed. In such a machine an oil cooling means therefore is unnecessary and since it would constitute an item of expense without serving a compensating function, would be undesirable.

In my copending application Serial No. 609,836, filed September 14, 1956, now Patent No. 2,976,831, granted March 28, 1961, there is disclosed a universal sewing machine which is designed to be fitted to sew either a single line of stitching or a plurality of lines of stitching and to be fitted with a number of different attachment mechanisms that can be used selectively for any specific sewing operation. When fitted for a high speed straight-away sewing operation overheating of the lubricant in this machine becomes a problem and requires a lubricant cooling means whereas when fitted for other operations which are performed at slower operating speeds, this problem does not exist. Therefore, to be truly universal, the machine must be adapted to be provided with an effective lubricant cooling means when required and also to be provided without a lubricant cooling means when it is not required. The machine must also be adapted to have a lubricant cooling means subsequently added to it or removed from it if it is later converted.

In accordance with the above, the object of this invention is to provide a lubricant cooling means for a sewing machine that can be selectively applied to the machine when required. It is also an object of this invention to provide a lubricant cooling means which is such that the provision on the machine for accommodating the same is relatively simple so that it will not have an appreciable effect upon the manufacturing cost of the machine and therefore, costwise, will not burden the machine when a lubricant cooling means is not required. It is a further object of this invention to provide a lubricant cooling means in which the provision on the sewing machine for accommodating it can be readily and economically sealed when the machine is not fitted with a lubricant cooling means. It is also an object of this invention to provide a lubricant cooling means which can be readily applied to and removed from the machine, is very stable and durable, efficient, and dependable having

2

in mind the heavy demands placed upon industrial sewing machines, and which is relatively economical not only in itself but also in the required supporting means and in the connections with the machine.

Having in mind the above and other objects that will be evident from an understanding of this disclosure, the invention comprises the devices, combinations and arrangements of parts as illustrated in the presently preferred embodiment of the invention which is hereinafter set forth in such detail as to enable those skilled in art readily to understand the function, operation, construction and advantages of it when read in conjunction with the accompanying drawings in which:

FIG. 1 is a fragmentary plan view of a sewing machine together with its drive means and supporting structure, and having a lubricant cooling means in accordance with the present invention.

FIG. 2 is a staggered vertical sectional view transversely of the machine of FIG. 1 and illustrating the mounting of the lubricant cooling means and the connections with the bed of the sewing machine.

FIG. 3 is a fragmentary detail sectional view taken substantially on the line 3—3 of FIG. 2.

With reference to the drawings, there is illustrated a sewing machine 1 that is substantially as disclosed in my above noted prior application Serial No. 609,836 to which reference may be had for a detailed description thereof. The machine 1 is herein disclosed only insofar as is necessary for an understanding of the present invention.

The sewing machine 1 includes a hollow frame comprising a bed 2 from the one end of which rises a standard 3 that carries a bracket arm 4 terminating in a head 5 overhanging the bed 2. The hollow interior of the bed 2, FIG. 2, is closed by a bottom wall 6, a front wall 7 and a rear wall 8 integral with and upstanding from the bottom wall 5, and a gasketed oil-tight cover plate 9 to define a closed splash lubricated compartment 2a. The operating mechanism within the bed 2 includes a main shaft 10 journaled longitudinally thereof and having a bevel gear 11 that meshes with a similar gear 12 on a looper drive shaft 13 journaled transversely of the bed. A spur gear 14 is also mounted on the main shaft 10 adjacent to the gear 11 and meshes with a similar gear 15 on a feed actuating shaft 16 journaled in the bed 2 parallel to the main shaft 10.

The sewing machine 2 is mounted upon a table top 17 and is driven by an electric power transmitter 18 mounted on the underside of the table top 17. The transmitter 18 is as disclosed, for example, in the patent of Ingalls, No. 2,739,251, March 20, 1956, to which reference may be had. Insofar as concerns the present invention it is sufficient to note that the transmitter 18 includes an internal cooling means which draws air into the same as indicated by the arrows A in FIG. 1 and exhausts it as indicated by the arrows B.

The table top 17 is supported by a stand that includes two pairs of upstanding legs 19 and 20. The right hand pair of legs 20 comprises a front leg 21 and a rear leg 22 which in the usual manner, are U-shaped in cross section and are formed of sheet metal. For vertical adjustment, the legs 21 and 22 are formed in two parts, the rear leg 22 having a lower portion 23 and an upper portion 24 that are secured together in vertically adjusted position by a bolt 25 and a cooperating nut 26, with the bolt 25 extending through an aperture in the base web of the lower portion 23 and through a vertically elongated slot 27 in the base web of the upper portion 24. The front leg 21 comprises a lower portion 28 and an upper portion 29 that are secured together in vertically adjusted position by a bolt 30 and a cooperating nut 31, the bolt 30 extending through an aperture in the base web

of the low portion 28 and through a vertically elongated slot 32 in the base web of the upper portion 29. At their upper ends, the upper sections 24 and 29 extend between and are spot welded to the depending webs of an inverted U-shaped top piece 33 that is secured to the underside of the table top 17 by bolts as at 34 and cooperating nuts 35. At an intermediate point, the legs 21 and 22 are connected together by an inverted U-shaped cross piece 36 that at its ends extends between and are spot welded to the side webs of the lower portions 23 and 28.

A lubricant cooling radiator 37 is mounted on the right hand pair of legs 20 in a position such that the exhaust which is indicated by the arrows B from the transmitter 18 will impinge upon it and thus cause a circulation of air around the radiator 37 to enhance the conduction of heat therefrom. The radiator 37 is substantially rectangular and has corrugated external surfaces as illustrated in FIG. 3 which serve to increase the heat dissipating area. The top of the radiator 37 is closed by a gasketed oil-tight cover plate 38 that is secured by screws 39 and has an oil filling aperture that is closed by a screw plug 40. A drain aperture which is closed by a screw plug 41 is provided in the bottom of the radiator 37.

For mounting the radiator 37 on the pair of legs 20, there are provided a pair of vertically arranged straps 42 which are secured to the radiator by screws 43 that extend through apertures in the straps 42 and are threaded into bosses 44 on the inside of the radiator. At their upper ends the straps 42 are secured to the outer depending web of the top piece 33 by bolts 45 and cooperating nuts 46 while at their lower ends they are secured to the outer depending web of the cross piece 36 by bolts 47 and cooperating nuts 48.

The radiator 37 is connected to the hollow interior of the bed 2 by means of a pair of flexible rubber tubes 49 and 50. The tube 49 which conducts the heated lubricant from the bed 2 by means of a fitting 51 including a nipple 52 having an axial bore 53 and a threaded end 54 that is threaded through a tapped bore 54a in the bottom wall 6 of the bed 2. The nipple 52 also includes a second externally threaded end 55 which has an annular slot 56 extending inwardly from the end thereof for receiving the end of the tube 49 and in which it is secured and sealed by a wedge-shaped collar 57 that surrounds the tube 49 and is forced into the slot 56 by a nut 58 threaded onto the end 55 and having an integral shoulder 59 for engaging the collar 57 and a second internal shoulder 60 for tightening the nut 58 against the end of the nipple 52. At its opposite end, the tube 49 is connected to the interior of the radiator 37 at the top thereof by a fitting 61 that is the same as the fitting 51.

Within the bed 2, there is press fitted within the bore 53 of the nipple 52, a vertically arranged standpipe 62 that rises to a point adjacent to the cover plate 9 and constitutes a vertical extension of the tube 49 within the lubricant chamber to close the tube to a point above the level of the lubricant in the compartment. An oil collecting plate or pan 63 is secured to a mounting bar 64 that is in turn secured to the underside of the cover plate 9 and includes a spout 65 that communicates with the top of the standpipe 62 for conducting lubricant deposited on the plate 63 into the standpipe 62.

The tube 50 is connected at its opposite ends by fittings 66 and 67 which are identical to the fitting 51, to the bottom wall 6 of the bed 2 and to the bottom of the radiator 37. The tube 50 conducts the cooled lubricant from the bottom of the radiator 37 and discharges it into the bottom of the bed 2.

During the operation of the machine, the bed 2 is filled with lubricant approximately to the level indicated by the line 68 in FIG. 2, which is the normal operating level, and the radiator 37 and the tubes 49 and 50 are completely filled. When the machine is operated, parts 75

of the mechanism within the bed, for example, the gears 14 and 15 which are partly immersed in the lubricant, agitate the lubricant to splash lubricate the mechanism within the bed. Some of the lubricant which is impelled

5 by the mechanism in the bed is deposited on the plate 63 and is drained therefrom through the spout 65 into the standpipe 62. The level of the lubricant in the standpipe 62 is thus raised above the level of the lubricant in the bed and a head is created which will force the lubricant down the tube 49 and into the top of the radiator 37 and at the same time will force the cooled lubricant out of the bottom of the radiator 37 through the tube 50 and into the bottom of the bed 2. Because of the difference in the specific gravity between the hot lubricant and 15 the cooled lubricant, the cooled lubricant will tend to remain at the bottom in the bed 2 and thus force the hot lubricant toward the surface. For the most part, it is the hot lubricant which is thrown onto the plate 63 and delivered to the radiator 37. Within the radiator 37, 20 the hot lubricant will tend to remain at the top and will settle to the bottom as it cools and as additional hot lubricant is delivered to the radiator. Thus, only the cooled lubricant will pass from the radiator 37 and through the tube 50 into the bottom of the bed 2.

25 To accommodate a lubricant cooling means in accordance with the present invention, the sewing machine need be provided only with two tapped bores in the bottom wall 6 for receiving the fittings 51 and 66. To mount the radiator 37, the stand is provided only with the apertures for accommodating the bolts 45 and 47. When the machine is fitted for an operation in which a lubricant cooling means is not required, it is necessary only to close the bores in the bottom wall 6 as by screw plugs. Thus, there is no appreciable expense in adapting the 30 machine for the use of the present lubricant cooling means. At the same time, the lubricant cooling means may be subsequently added to or removed from the machine in the event that it is converted so that a cooling means becomes either necessary or unnecessary as the 35 case may be. Not only can the radiator be readily mounted on the stand, but it is mounted for very effective cooling in that it is directly in the exhaust from the transmitter 18.

Having thus set forth the nature of the invention, what 40 I claim herein is:

1. In combination, a support, a sewing machine mounted upon said support and including a bed having a closed lubrication compartment adapted to be filled with lubricant to a normal operating level and having operating 45 mechanism in said closed lubrication compartment with a portion thereof adapted to dip into the lubricant for agitating the lubricant and thereby splash lubricating the mechanism in said compartment, said bed including a bottom wall having two tapped apertures opening into said 50 closed compartment, and lubricant cooling means comprising a radiator carried by said support, an outlet conduit and a return conduit, means comprising fittings having nipples threaded into said apertures for securing one end of said conduits to and in communication with said 55 closed compartment, means for securing the other end of said outlet conduit to and in communication with the top portion of said radiator, means for securing the other end of said return conduit to and in communication with the bottom of said radiator, means comprising an extension of said outlet conduit for closing said outlet conduit to a point above the level of the lubricant in said 60 closed compartment, and means within said closed compartment for directing lubricant impelled by said operating mechanism into said outlet conduit.

2. In combination, a support, a sewing machine mounted upon said support and including a bed having a closed lubrication compartment adapted to be filled with lubricant to a normal operating level and having operating mechanism in said closed compartment with a portion 65 adapted to dip into the lubricant for agitating the lu-

bricant and thereby splash lubricating the mechanism in said compartment, said bed including a bottom wall having two tapped apertures opening into said closed compartment, and lubricant cooling means comprising a radiator carried by said support, an outlet conduit and a return conduit, means comprising fittings having nipples threaded into said apertures for securing one end of said conduits to and in communication with said closed compartment, means for securing the other end of said outlet conduit to and in communication with the top portion of said radiator, means for securing the other end of said return conduit to and in communication with the bottom of said radiator, a standpipe within said closed compartment and connected to the fitting for said outlet conduit with the upper end of said standpipe being disposed above the level of the lubricant in said closed compartment and the bottom of said standpipe being in open communication with said outlet conduit, and means within said closed compartment for directing lubricant impelled by said operating mechanism into the upper end of said standpipe.

3. In combination, a stand comprising a table top and opposed pairs of legs at the opposite ends of said table top for supporting said table top, a sewing machine mounted upon said table top, said sewing machine including a bed having a closed lubrication compartment adapted to be filled with lubricant to a normal operating level and having operating mechanism in said closed lubrication compartment with a portion thereof adapted to dip into the lubricant for agitating the lubricant and thereby splash lubricating the mechanism in said compartment, said bed including a bottom wall having two tapped apertures opening into said closed compartment, and lubricant cooling means comprising a radiator mounted upon the pair of legs at one end of said stand, an outlet conduit and a return conduit, means comprising fittings having nipples threaded into said apertures for securing one end of said outlet conduit and one end of said return conduit to and in communication with said closed compartment, means for securing the other end of said outlet conduit to and in communication with the top of said radiator, means for securing the other end of said return conduit to and in communication with the bottom of said radiator, means comprising an extension of said outlet conduit for closing said outlet conduit to a point above the normal operating level of the lubricant in said closed compartment, and means within said closed

compartment for directing lubricant impelled by said operating mechanism into said outlet conduit.

4. In combination, a stand comprising a table top and opposed pairs of legs at the opposite ends of said table top for supporting said table top, a sewing machine mounted upon said table top, said sewing machine including a bed having a closed lubrication compartment adapted to be filled with lubricant to a normal operating level and having operating mechanism in said closed lubrication compartment with a portion thereof adapted to dip into the lubricant for agitating the lubricant and thereby splash lubricating the mechanism in said compartment, said bed including a bottom wall having two tapped apertures opening into said closed compartment, 10 drive means for said sewing machine comprising a transmitter mounted upon the underside of said table and having means for circulating cooling air through said transmitter, and lubricant cooling means comprising a radiator mounted upon the pair of legs at one end of said stand 15 and in position to be impinged upon by the exhaust of the cooling air from said transmitter, an outlet conduit and a return conduit, means comprising fittings having nipples threaded into said apertures for securing one end of said outlet conduit and one end of said return conduit to and in communication with said closed compartment, means for securing the other end of said outlet conduit to and in communication with the top of said radiator, means for securing the other end of said return conduit to and in communication with the bottom of said radiator, means comprising an extension of said outlet conduit for closing said outlet conduit to a point 20 above the normal operating level of the lubricant in said closed compartment, and means within said closed compartment for directing lubricant impelled by said operating mechanism into said outlet conduit.
